CLAIM

The ornamental design for a corrugated packing element, as shown and described.

DESCRIPTION

FIG. 1 is an upper perspective view of an exemplary embodiment of a corrugated packing element, showing my new design;

FIG. 2 is a lower perspective view thereof;

FIG. 3 is a front perspective view thereof;

FIG. 4 is a rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is an upper perspective view thereof, shown in a position of use with an exemplary corrugated packing element;

FIG. 12 is a top view thereof;

FIG. 13 is a bottom view thereof;

FIG. 14 is an upper perspective view thereof, shown in an alternate position of use with an exemplary corrugated packing element;

FIG. 15 is a top view thereof; and,

FIG. 16 is a bottom view thereof.

The broken lines are shown for the purpose of illustrating environmental subject matter of an exemplary corrugated packing element and form no part of the claim.
